UNITED STATES PATENT OFFICE

2,654,228

DEVICE FOR FREEZING AND DISPENSING
ICE CUBES

Robert W. Templar, West Sacramento, Calif.

Application December 3, 1951, Serial No. 259,555

4 Claims. (Cl. 62—4)

1

This invention relates to new and useful improvements in refrigerating apparatus and the primary object of the present invention is to provide a device for freezing ice to multiple cube form and then sequentially ejecting the cubes into a container.

Another important object of the present invention is to provide a device for making and dispensing ice cubes involving a tray and an endless conveyor having a horizontally movable finger supporting portion that travels through the tray after ice cubes have been formed to forcibly eject the cubes from the tray.

A further object of the present invention is to provide an ice cube former wherein the fingers of the conveyor function as separators between which the cubes are formed.

A still further aim of the present invention is to provide a device of the aforementioned character that is simple and practical in construction, strong and reliable in use, neat and attractive in appearance, efficient and durable in operation, convenient to install, service and repair, inexpensive to manufacture, and otherwise well adapted for the purpose for which the same is intended.

Other objects and advantages reside in the details of construction and operation as more fully hereinafter described and claimed, references being had to the accompanying drawings forming part hereof, wherein like numerals refer to like parts throughout, and in which:

Figure 1 is a vertical sectional view of a cabinet or refrigerator and showing the present invention mounted therein;

Figure 2 is an enlarged transverse vertical sectional view taken substantially on the plane of section line 2—2 of Figure 1;

Figure 3 is a plan view of Figure 2; and

Figure 4 is a vertical sectional view taken substantially on the plane of section line 4—4 of Figure 3.

Referring now to the drawings in detail, wherein for the purpose of illustration, there is disclosed a preferred embodiment of the present invention, the numeral 10 represents an elongated horizontally supported tray or trough having an upwardly and forwardly curved end 12. The tray is constructed of metal to rigidly conduct heat.

Tray 10 is supported within a refrigerator or the like 14 having the usual refrigerator coils or tubes 16 that are disposed sufficiently close to the tray to freeze a liquid, such as water, in the tray.

A pair of spaced parallel, suitably connected,

walls 18 are mounted in the refrigerator and the tray is disposed between the lower portions of these walls. Forward and rear horizontal shafts 20 and 22 are rotatably supported by bearings and extend between the walls 18 and carry sprockets 24 and 26, respectively, which are located between the walls 18.

The forward ends of walls 18 project forwardly from the end 12 of tray 10 and rotatably support a horizontally disposed drive shaft 28 carrying a sprocket 30 that is located above the sprockets 24 and 26, and above and in front of the end 12. An endless conveyor or sprocket chain 32 extends about the sprockets 24, 26 and 30. The conveyor 32 supports a plurality of longitudinally spaced rigid fingers or separator plates 34.

The conveyor 32 is provided with a horizontally disposed lower flight 36 that extends longitudinally of the tray and which overlies the tray. The fingers 34 carried by the lower flight depend into the tray to permit the formation of ice cubes between adjacent fingers of this horizontal portion 36.

In practical use of the present invention, the refrigerator is provided with a suitable liquid dispenser 38 whose inlet will be the main water supply line and whose discharge conduit 40 is located over the rear end of the tray 10 to supply water or the like to the tray and permit a constant level of liquid in the tray.

The shaft 28 is operatively connected through reduction gearing in casings 42, to an electric motor 44 whose operation is controlled by an electric timer 46 of suitable type. The timer 46 may also be electrically connected to the refrigeration system of the refrigerator to complete a current to motor 44 during or slightly after defrosting of the refrigerator or freezing unit.

The ice cube separators remain stationary during the freezing cycle of the refrigerator with the separators on the lower flight 36 disposed within the tray. When the cubes are frozen the condensing unit (not shown) of the refrigerator or the freezing cycle stops and defrosting takes place causing actuation of the power means 44. As the means 44 operates flight 36 will move toward end 12 to forcibly eject the cubes from end 12 and into a container 48 therebeneath.

The sprockets will rotate sufficiently to move out beyond the end 12 of tray 10 the required number of ice cubes which in turn gravitate into container 48. At this time the refrigeration cycle repeats and additional water is dispensed into the tray with the motor 44 at rest.

Obviously, movement of the conveyor may be regulated by other means than that described and may be manually accomplished in a low price unit. Also, the tray may be filled all at once or gradually depending upon many factors, such as the size of tray, capacity of the tray or refrigerator, etc.

Although the drawings show a single tray or trough any suitable number may be employed. Possibly 2 sets of trays each consisting of or containing 1, 2, 3 or more either stationary or movable partitions so as to form 1, 2, 3 or more ice cubes abreast at one time, will be used. Then while these are defrosting another set of equal or like capacity could be forming.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and the scope of the appended claims.

Having described the invention, what is claimed as new is:

1. An apparatus for freezing and dispensing ice cubes comprising a stationary horizontally disposed tray adapted to receive a freezable liquid, cooling means adjacent the tray for freezing the liquid therein, an endless conveyor having a lower flight overlying the tray, longitudinally spaced fingers carried by the conveyor, the fingers on the lower flight of said conveyor depending into said tray, whereby ice formed between adjacent fingers on said lower flight will be urged from the tray during rotation of said conveyor, and a timer mechanism operatively connected to said conveyor and the cooling means for moving the conveyor after defrosting of the cooling means.

2. For use with a horizontally supported tray having an upwardly curved end and a refrigeration system including refrigerated coils disposed adjacent the tray for freezing a liquid in the tray, an endless conveyor supported for rotation above the tray and having a lower horizontal

flight paralleling the tray and movable toward the said curved end of the tray, and a plurality of longitudinally spaced fingers carried by the conveyor, the fingers on the lower flight of said conveyor depending therefrom and being disposed in said tray to form separators between which ice cubes will be formed, and a timer mechanism operatively connected to the conveyor and to the refrigeration system for moving the conveyor after defrosting of the refrigeration system.

3. The combination of claim 2 wherein said conveyor includes supporting sprockets, one of said sprockets being disposed above the other sprockets and above and in front of said curved end.

4. An apparatus for freezing and dispensing ice cubes comprising a tray having an upwardly curved end, means for periodically supplying a liquid into the tray, refrigeration means adjacent the tray for freezing a liquid in the tray, and timer actuated means operatively connected with said refrigeration means for ejecting ice cubes from the curved end of the tray after deactivation of said refrigeration means, said ejecting means including an endless conveyor disposed above the tray and having a lower flight overlying the tray and movable longitudinally toward said curved end, and fingers carried by the conveyor, the fingers on the lower flight of said conveyor being disposed in said tray.

ROBERT W. TEMPLAR.
